UNITED STATES PATENT OFFICE.

HARRY A. KUHN, OF PITTSBURGH, PENNSYLVANIA.

METHOD OF MINING COAL

1,237,061.

Specification of Letters Patent. Patented Aug. 14, 1917.

Application filed May 18, 1914. Serial No. 839,326.

To all whom it may concern:

Be it known that I, HARRY A. KUHN, a citizen of the United States, and resident of Pittsburgh, in the county of Allegheny and State of Pennsylvania, have invented a new and useful Improvement in Methods of Mining Coal; and I do hereby declare the following to be a full, clear, and exact description thereof.

10 My invention relates to method of mining coal.

In an application filed by me October 21, 1913, Serial No. 796,497, I described and claimed a method of mining coal which consists essentially in making an undercut in the body of the coal, expanding the coal along its lines of cleavage by shooting, whereby the coal settles down into the undercut, undermining this mass of coal and conveying it away.

The present invention is included within the broad claims of the above application and in addition to undermining the coal and conveying it away, by the present method I apply a pressure at an angle to the undermining cut and simultaneously therewith so that the expanded coal is subjected to a pressure which tends to release the coal of its adhesions along the lines of cleavage, and at the same time breaking up any band or bands in the wall of coal which would have a tendency to bridge the coal above said bands and prevent its dislodgment during the undermining or undercutting process.

35 In the accompanying drawings I have illustrated apparatus suitable for carrying out my invention in which Figure 1 is a plan view of the machine; Fig. 2 is a side elevation; Fig. 3 is a like view partly in section showing the machine in its raised position; Fig. 4 is a detail, and Fig. 5 is a section on the line 5—5 Fig. 4.

The apparatus which I am about to describe forms the subject of a separate application filed of even date herewith, Serial No. 839,327.

The numeral 2 designates a suitable frame which may be composed of beams, angle-bars, etc., united to form a rigid construction. This frame is supported normally in an inclined position, its rear end being carried by the truck 3, which is provided with the axle 4 on which the traction wheels 5 are mounted. The wheels 5 and the mechanism for driving same are housed in the box

or casing 6. Within the casing 6 on the axle 4 is the friction sheave 7 which is engaged by the friction sheave 8 on the shaft 9. This shaft 9 is suspended from the bars 10 which are pivoted to the bracket 11. The toggle member 12 is connected to the shaft 9 and said toggle is pivoted at 13 to the link 14 which is pivoted to the lug 15 on the casing 6. The other end of the toggle is connected to the crank arm 16 on the stud shaft 17 which is mounted on the bracket 18. To the outer end of the stud shaft 17 is connected the operating lever 19. It is apparent that by operating the lever 19, the toggle member 12 is operated to move the friction member 8 into or out of contact with the friction sheave 7 to transmit power to the driving axles.

Mounted on the shaft 9 is a sprocket wheel 20, the chain 21 passing around the sprocket wheel 20 and around the sprocket wheel 22 of the shaft 23 mounted in the frame. Mounted on the shaft 23 is the worm wheel 24 which is connected with the worm 25 on the shaft 26. This shaft 26 has the gear wheel 27 which is engaged by the pinion 28 on the counter shaft 29. The gear wheel 30 on the shaft 29 is engaged by the driving pinion 31 on the shaft 32. The shaft 32 has the clutch box 33 adapted to receive the square end of the shaft 34 of the motor 35. This motor, which in the present case is an electric motor, is the driving power for the undercutting mechanism 36, which may be of the ordinary construction, comprising a cutter chain which is driven by power transmitted from the motor 35. When the undercutting mechanism is mounted on the frame 2, the motor shaft 34 engages the clutch 33, and power is transmitted from the motor to the mechanism for connecting the traction wheels 5 to the other parts of the mechanism to be hereafter described.

In front of the truck 3 are the steering wheels 40 which support the forward end of the frame 2. Channels 41 are secured to the frame 2, said channels being inclined and the flanges of said channels forming a track for the rollers 42 of the buggy 43. The buggy 43 has the threaded nut 44 with which the threaded bar 45 engages. The upper end of the threaded bar has the pinion 45* which meshes with the pinion 46 on the shaft 47. This shaft 47 has the gear wheel 48 which meshes with the gear wheel 27. By the rota-

tion of the threaded bar 45 the buggy is advanced with its rollers 42 moving in the channel bars 41, and in this way the front end of the frame 2 is lifted, as indicated in 5 Fig. 3.

To operate the steering wheels 40, hand wheels 49 are provided mounted on the shaft 50, said shaft carrying the worm 51 which engages the toothed sector 52 on the swivel 10 plate 53 of the truck 43. In this manner, the steering wheels are properly directed to move the machine in the direction desired.

At the rear end of the frame 2 is the sprocket wheel 55, and at the forward end 15 of said frame are the sprocket wheels 56. The chain 57 passes around said sprocket wheels and said chain carries the flights 58 at intervals. The outer ends of the flights 20 58 are formed with integral cutters or diggers 58^a, or if desired, said cutters or diggers may be made detachable and are adapted to cut or dig under the body of coal which has been lowered by shooting, as fully hereinafter set forth. The cutters on 25 the flights are preferably arranged alternately extending upwardly and downwardly so as to make a wider cut.

The front edges of the flights are preferably beveled to an edge as indicated at 59, 30 to enable them to pass more readily through the mass of coal.

The pan 60 is secured to the frame 2 below the flights and said flights are adapted to travel along the said pan and convey the 35 coal which is dislodged onto said pan by the action of the diggers or cutters. The coal is discharged at the rear into the pit wagon 61.

In carrying out my improved method with the above described apparatus, it would be 40 assumed that the undercut has been made in the solid wall of coal, and that the coal has been expanded along its lines of cleavage by shooting, all as clearly set forth in the application Serial No. 796,497, above referred to.

I then proceed to undermine this expanded body of coal by advancing the machine along the floor of the mine and digging under the coal as indicated in Fig. 2 of the 50 drawings to form a crevice like opening. After the cutters and flights have advanced the proper distance under the mass of coal, I then apply the pressure at an angle thereto, or upwardly as in the present case, and 55 this is accomplished by putting in operation the mechanism to raise the forward end of the machine simultaneously with the undermining or dislodging mechanism. Accordingly the feed screw 45 is rotated and the 60 buggy 43 moved along the guides 41 in the frame and as said buggy moves forwardly the frame is gradually raised as indicated in Fig. 3. This raising of the frame creates the upward pressure on the mass of 65 coal and where there are any bands, as at

65, these bands will be broken and the coal which has been expanded along its lines of cleavage will be dislodged in lumps so as to be deposited on the pan and carried off by the flights to the pit wagon in the rear. 70

In this manner, I provide for the dislodging of the coal which has been expanded along its lines of cleavage and not disturbed by the shooting so as to break up the mass of coal into slack or small lumps. The coal 75 is released of its adhesions partially along its lines of cleavage and when the support is dislodged from underneath by the forces acting in the cut the coal is removed in large lumps. Furthermore, where bands are 80 present, which cause a bridge of the coal above said bands, by my improved method said bands are disrupted and the coal above the seam removed without difficulty. The mere undermining of the coal which has 85 been expanded along its lines of cleavage where bands are present may only act to dislodge the coal below the bands, while by the above method the removal of all the coal above the bands is assured. If desired, the 90 bands of slate may be removed by the cutters 58^a, or the front end of the machine could be elevated and the coal above the bands first removed and then the bands removed. The coal below the bands would be 95 removed afterward.

What I claim is:

1. The method of mining coal, consisting in making an undercut in the solid of the coal, introducing within the solid of the 100 coal expanding forces whereby the coal is expanded into the cut, loosened from the surrounding solid, released or cracked along its lines of cleavage, and settled substantially as a mass of cracked coal in place, subsequently forming a crevicelike opening in the mass of loosened coal by the application of continuous horizontally traveling forces, and simultaneously therewith applying a force traveling continuously at an angle to 105 the plane of the crevicelike opening, thereby dislodging the coal with the traveling forces, and simultaneously carrying away the dislodged coal.

2. The method of mining coal, consisting in 115 making a cut in the solid of a seam of coal, expanding and disrupting the solid coal along lines of its cleavage, whereby the coal acted upon is loosened from the surrounding solid and cracked along lines of its cleavage, 120 subsequently forming a crevicelike opening in the loosened mass of coal by means of traveling forces, and simultaneously therewith applying a force traveling continuously at an angle to the direction of the 125 traveling forces within the crevicelike opening, dislodging the coal, and conveying it away.

3. The method of mining coal, consisting in 130 making a cut in the solid of a seam of

coal, expanding and disrupting the solid coal along lines of its cleavage, whereby the coal acted upon is loosened from the surrounding solid and cracked along lines of its cleavage, subsequently forming a crevice-like opening in the loosened mass of coal, applying a force traveling continuously at an angle to the plane of operation of the first traveling forces, simultaneously there-

with dislodging the coal, and conveying it away.

In testimony whereof I, the said HARRY A. KUHN, have hereunto set my hand.

HARRY A. KUHN.
